[57] CLAIM

The ornamental design for a spout or the like, as shown and described.

DESCRIPTION

FIG. 1 is a left side elevational view of a spout or the like embodying our new design, the right side being a mirror image of the left side shown;

FIG. 2 is a front elevational view thereof;

FIG. 3 is a rear elevational view thereof;

FIG. 4 is a top plan view thereof;

FIG. 5 is a bottom plan view thereof;

FIG. 6 is a perspective view taken from the top, front and left side thereof;

FIG. 7 is a left side elevational view of a second embodiment thereof, the right side being a mirror image of the left side shown;

FIG. 8 is a front elevational view of FIG. 7;

FIG. 9 is a rear elevational view of FIG. 7;

FIG. 10 is a top plan view of FIG. 7;

FIG. 11 is a bottom plan view of FIG. 7; and

FIG. 12 is a perspective view taken from the top front and left side of FIG. 7.
